(57) **CLAIM**

The ornamental design for vehicle cigarette lighter power adapter, as shown and described.

DESCRIPTION

FIG. 1 is a perspective top view of the vehicle cigarette lighter power adapter of the invention, with a portion of the power supply cord shown in phantom.

FIG. 2 is top plan view of the vehicle cigarette lighter power adapter of FIG. 1, with a portion of the power supply cord shown in phantom.

FIG. 3 is a bottom plan view of the vehicle cigarette lighter power adapter of FIG. 1, with a portion of the power supply cord shown in phantom.

FIG. 4 is a left side view of the vehicle cigarette lighter power adapter of FIG. 1, with a portion of the power supply cord shown in phantom.

FIG. 5 is a right side view of the vehicle cigarette lighter power adapter of FIG. 1, with a portion of the power supply cord shown in phantom.

FIG. 6 is a front view of the vehicle cigarette lighter power adapter of FIG. 1; and,

FIG. 7 is a rear view of the vehicle cigarette lighter power adapter of FIG. 1.

The power supply cord leading out of the front of the vehicle cigarette lighter power adapter of FIGS. 1-5 shown in phantom lines forms no part of the design.
